UNITED STATES PATENT OFFICE.

EDWARD AMBROSE, OF TROY, NEW YORK, ASSIGNOR TO ENTERPRISE GAS STOVE MANUFACTURING COMPANY, OF NEW YORK, N. Y., A CORPORATION OF NEW YORK.

DESIGN FOR STOVE.

SPECIFICATION forming part of Design No. 36,290, dated April 14, 1903.

Application filed March 4, 1903. Serial No. 146,234. Term of patent 7 years.

To all whom it may concern:

Be it known that I, EDWARD AMBROSE, a citizen of the United States, and a resident of Troy, Rensselaer county, and State of New York, have invented a new, original, and ornamental Design for a Stove, of which the following is a specification.

The leading feature of my design consists in a stove having the particular shape and ornamentation shown in the accompanying drawing, which is a perspective view of said stove.

The stove is of generally prismatic shape, with rounded upper corners A and ornamental side posts B, which are located at the front of the stove and made in the nature of fanciful columns, with chalice-shaped capitals B' at the top. The legs C extend outwardly from the bottom of the stove and are orna-

mented with scrollwork, as is also a curved member C', which connects the two front legs. The door D has a rectangular frame of convex members D', which have scrollwork at the corners, while from the central field of the door rises an ornamental shield E.

I claim as my invention and desire to secure by Letters Patent—

The new, original and ornamental design for a stove, substantially as shown and described.

In testimony whereof I have signed my name to this specification in the presence of two subscribing witnesses.

EDWARD AMBROSE.
